Inventor:

By his Atty F. W. Richard.

UNITED STATES PATENT OFFICE.

GEORGE HORNECKER, OF ASTORIA, NEW YORK, ASSIGNOR TO ROBERT GAIR COMPANY, OF NEW YORK, N. Y., A CORPORATION OF NEW YORK.

TILTING DISPLAY GOODS CONTAINER.

Application filed August 17, 1922. Serial No. 582,489.

To all whom it may concern:

Be it known that I, GEORGE HORNECKER, a citizen of the United States, residing in Astoria, New York city, in the county of 5 Queens and State of New York, have invented certain new and useful Improvements in Tilting Display Goods Containers, of which the following is a specification.

The present invention relates to containers 10 formed by folding, and particularly to display containers, and one object is to provide a one-piece side-opening container formed by folding.

Another object is to provide a one-piece 15 side-opening container formed by folding having means for supporting the container in a tilted or inclined position for displaying characteristic matter arranged on the top of the container.

Another object is to provide a one-piece 20 side-opening container formed by folding, having a display flap and having means for supporting the container in a tilted or inclined position for displaying characteristic matter arranged on the top and display flap 25 of the container.

I attain these and such other objects as 30 may appear during the description by way of example in the subjoined specification of one of the possible embodiments of the invention shown in the accompanying drawings in which Figure 1, is a view of the blank from which the container is formed by folding the blank.

Figure 2, is a perspective view of the container in closed condition, the display flap being in display position and the container supported in a tilted or inclined position by a prop or rest which normally is a part of 40 the bottom of the container but is movable to position for providing the prop or rest, and

Figure 3, is a perspective view on a smaller scale than Figs. 1 and 2, of the container 45 in partially assembled folded form.

Similar reference characters denote similar parts throughout the several views.

The blank from which the container is 50 formed by folding the blank is of cardboard or other suitable material, of strip form with side extensions, the width of the strip being the desired width of the container, and comprises the display flap section 10, the top-forming section 11, the side-forming extensions 12 and 13, having the

adjoining side-tuck extensions 14 and 15, the front end-forming section 16 having the end-tuck extensions 17 and 18, the bottom-forming section 19 having the prop or rest 20, the rear end-forming section 21 having 60 the end tuck extensions 22 and 23, and the attaching tuck section 24.

The width of the display flap section 10 is the width of the blank, the length of the section 10 being sufficient for suitably displaying the characteristic matter arranged thereon, in the present instance this being somewhat less than the length of the top-forming section 11.

The length of the top-forming section 11 70 is the desired length of the container, and its width is the width of the main portion of the blank. The top-forming section 11 is defined from the display flap section 10 by the transverse fold scoring 25, and has on 75 one side thereof the side-forming extension 12 and on the other side thereof the side-forming extension 13, being defined from the side-forming extension 12 by the longitudinal fold scoring 26 and defined from 80 the side-forming extension 13 by the longitudinal fold scoring 27.

The side-forming extension 12 in length is 85 the same as the length of the top-forming section 11, and in width is the desired depth or height of the container, the side-forming extensions 12 and 13 in Fig. 1, being broken for economizing space in the drawing. The side-forming extension 12 is defined from the side tuck extension 14 by the longitudinal 90 fold-scoring 28. The side-forming extension 13 is similar to the side-forming extension 12 and is defined from the side-tuck extension 15 by the longitudinal fold scoring 29. 95

The side-tuck extension 14 on its inner edge is in length the same as the length of the side extension 12, but may be as shown somewhat shorter on its outer edge for facilitating tucking in, the width of the side-tuck 100 extension 14 being made sufficient for tucking-in purposes. The side tuck extension 15 is similar in all respects to the side-tuck extension 14.

The front end-forming section 16 in 105 length is the width of the main portion of the blank, and its width is the same as the width of the side-forming extensions 12 and 13, that is, the desired depth or height of the container. The front end-forming section 110

16 is defined from the top-forming section 11 by the transverse fold scoring 30, and is defined from the end-tuck extensions 17 and 18 by the longitudinal fold scorings 31 and 32. The end-tuck extension 17 in length on its inner edge is the width of the front end-forming section 16, the end-tuck extension being shorter on its outer edge to facilitate tucking in, and its width is suitable for tucking in purposes. The end-tuck extension 18 is in all respects similar to the tuck extension 17.

The bottom-forming section 19 is in width the width of the main portion of the blank, and in length is the same as the top-forming section 11. The bottom-forming section 19 has foldably connected thereto the prop or back-rest 20, this prop or back-rest being formed by two parallel longitudinal cuts 33 and 34 connected by a transverse cut 35 in the bottom-forming section, the prop or back-rest 20 being foldably connected on its remaining side to the bottom-forming section. The bottom-forming section 19 is defined from the front end-forming section 16 by the transverse fold scoring 36.

The rear or inner end-forming section 21 in length is the width of the main portion of the blank, and its width is the same as the front end-forming section 16. The rear end-forming section 21 is defined from the bottom-forming section 16 by the transverse fold scorings 37 and 37', and is defined from the end-tuck extensions 22 and 23 by the longitudinal fold scorings 38 and 39.

The attaching tuck section 24 in length on its inner edge is the width of the main portion of the blank, but it is somewhat shorter on its outer edge to facilitate tucking in. In width the attaching tuck section 24 is made sufficient for tucking-in purposes.

The attaching tuck 24 is defined from the inner end-forming section 21 by the transverse fold scoring 40. The attaching tuck section 24 on its upper side or face is suitably gummed for providing a means for attachment thereof to the top-forming section 11 when the blank is folded so that the inner edge of the attaching tuck section 24 coincides with the transverse fold scoring 25, the attaching tuck section being brought into this relation by folding cooperation of the front end-forming section 16, the bottom-forming section 19 and the rear or inner end-forming section 21.

For foldably assembling the container, the attaching tuck 24 being foldably moved to the position above described relative to the top-forming section 11 and secured thereto, the end-tuck extensions 17 and 18 are folded inwardly on the scorings 31 and 32, and the end-tuck extensions 22 and 23 are folded inwardly on the scorings 38 and 39, so that these end-tuck extensions are arranged on the line of the side edges of the top-forming

section 11; the side-forming extensions 12 and 13 are folded on the scorings 26 and 27, and the side-tuck extensions 14 and 15 are folded on the scorings 28 and 29, and the side extensions 12 and 13 are then tucked between the bottom edges of the end-tuck extensions 17, 18, 22 and 23 and the inner surface of the bottom-forming section 19, the side-tuck extensions 12 and 13 being frictionally retained in position and the container being in closed condition. For access to the interior of the container, a side extension 12 or 13, as the case may be, and its side-tuck extension, and the adjacent end-tuck extensions 17 and 22, or 18 and 23, as the case may be, are withdrawn from the container, thereby opening up the container at its side.

To place the container in display position the prop or back-rest 20 is withdrawn from the bottom-forming section 19 and bent on the scoring 37 until it is substantially at right angles to the bottom-forming section and forms a prop or rest for maintaining the container in tilted or inclined position shown in Fig. 2, the display flap 10 being bent on the scoring 25 and caused to stand at an angle to the bottom forming section 11, so that the characteristic matter on the bottom-forming section and the display flap may be brought conspicuously to attention.

It will be noted that when the prop or back-rest 20 is in supporting position an opening is left in the bottom of the container through which small articles can escape. To prevent this escape of small articles they may be enclosed in a common or general wrapping, not shown, of paper or other suitable material which in effect becomes an interior lining for the container and closes said opening.

The containers are well adapted for display in numbers or masses upon a counter or in a show case or window, the display flap of each container in addition to its use for displaying characteristic matter arranged thereon, affording a convenient means for lifting a desired container from its position among the other containers without disturbance of the other containers.

Having thus described my invention, it should be understood that there may be modifications thereof and variations therein without departing from the spirit of the invention, or exceeding the scope of the appended claims.

What I claim and desire to protect by Letters Patent is:—

1. A paper box formed from a blank having a rectangular top portion, side portions extending from the sides of the top portion and defined therefrom by fold lines, bottom edge flaps extending laterally from the side flaps and defined therefrom by fold lines, an end flap extending from one end of the

- top portion and defined therefrom by a fold line, a bottom portion extending from the end flap and defined therefrom by a fold line, an end flap extending from the bottom flap at the end remote from the first mentioned end flap, there being fold lines between the bottom portion and second end flap extending inwardly from each lateral edge, said bottom portion having a U-shaped 10 easel forming slit extending into the bottom portion from the inner ends of the last mentioned fold lines, and a glue flap extending from the second end flap and easel portion.
- 15 2. A paper box formed from a blank having a rectangular top portion, side portions extending from the sides of the top portion and defined therefrom by fold lines, bottom edge flaps extending laterally from the 20 side flaps and defined therefrom by fold lines, an end flap extending from one end

of the top portion and defined therefrom by a fold line, a bottom portion extending from the end flap and defined therefrom by a fold line, an end flap extending from the bottom flap at the end remote from the first mentioned end flap, there being fold lines between the bottom portion and second end flap extending inwardly from each lateral edge, said bottom portion having a U-shaped 25 easel forming slit extending into the bottom portion from the inner ends of the last mentioned fold lines, a glue flap extending from the second end flap and easel portion, and a display card extending from the top portion opposite the first end flap and defined from the top portion by a fold line.

GEORGE HORNECKER.
